UNITED STATES PATENT OFFICE

2,018,930

PISTON RING-GROOVE SCRAPER AND
GROOVE DEEPENER

Charles D. Stromgren, Los Angeles, Calif.

Application November 23, 1934, Serial No. 754,483

5 Claims. (Cl. 15—104.01)

The invention is intended for use as a hand tool by mechanics when piston ring grooves, particularly in pistons for internal combustion engines, require the removal of accumulated carbon or an increased depth in order to accommodate piston rings of increased thickness. In cutting or scraping tools, particularly those used in the metal arts and designated as hand tools, limitation of physical power and rigid relative holding means have prevented fullest realization of the results desired for the time and energy spent with most tools available.

As explained and described herein it will be recognized that my particular application of a semi-rigidly sustained cutting or scraping tool to the ring groove of an internal combustion engine piston and the improved predetermined relative aligning and holding means gives a less resistive material removal effect to the advancing cutting tool, and has less tendency to dig or gouge to uncuttable depth, than has heretofore been experienced with other forms of rigidly adjustable hand cutting or scraping ring groove tools.

25 The principal object of my invention is to provide a hand-scraping or cutting tool for internal combustion engine piston grooves that is adaptable through a range of different diametered pistons with different width ring grooves; 30 one that will scrape or cut rapidly as desired without digging or gouging and with the least possible effort, effecting a smooth surface over which it has cut.

The details in the construction of certain preferred forms of my invention together with other objects attending its production will be best understood from the following description and accompanying drawing which is chosen for illustrative purposes only:

40 Fig. 1 is an elevation of the device showing a piston 10 in position, preparatory to removing material from the ring groove 11. To illustrate more clearly the position of the bar 1 with its goose neck 1^a, a cutter 3, and ring groove 11, the piston 10 is shown on the line A A Fig. 2.

Fig. 2 is a plan of Fig. 1 showing the goose neck 1^a of bar 1 and cutting tool 3 inserted in ring groove 11 of piston 10.

Fig. 3 is an elevation of the device showing the cutter post in position for operation on larger sized pistons with spring 7 compressed.

Fig. 4 is an elevation of the device showing the cutter post close to the goose neck bar 1 with spring 7 extended.

55 Fig. 5 is an elevation of the device minus the

spring 7; the device may be operated this way as hereinafter explained.

Fig. 6 is an elevation of the device minus the cutter post height setting spring 5; the device may be operated in this manner as hereinafter 5 explained.

Fig. 7 is a detail plan of the revolvable cutter 3 which is held on the post in any conventional manner; in this use the post is riveted over.

Fig. 8 is an elevation of Fig. 7.

Fig. 9 is a detail plan of cutter post 2, adjusting nut 4, and a broken view of the goose neck on bar 1.

Fig. 10 is a detail end elevation of cutter post 2 with the adjusting nut 4 in half section, showing also a section of bar 1 inserted in slot 12 of cutter post 2.

More particularly describing the invention as illustrated, the cutter 3 is revolvably mounted on post 2 so that any one of the different width 20 members thereon, sized to fit standard grooves, may be turned to contact and cutting position as shown in Figs. 1 and 2.

Variation of longitudinal position of cutter 3, for cutting the grooves of different sized pistons, 25 is provided for by sliding movement of the post 2 on bar 1 on which cutter shaft 2 is slidably mounted. The bar 1 is made long enough to serve as a handle for operation of the device, which also gives added range of movement away 30 from the goose neck when placing a piston to cutting position or in making room for its removal.

It is obvious that the piston may be turned against the cutter 3, Fig. 1, contraclockwise, and 35 the device held to fixed position or piston held stationary and the device revolved clockwise around the piston for cutting material out of groove.

It will be seen in Fig. 5 that spring 7 as shown 40 in Fig. 1 is removed, also that in Fig. 6 spring 5 as shown in Fig. 1 is removed; the device may be used with either or both of the springs removed since their function is to make unnecessary any hand pressure directly against the cutter post for 45 feeding into the material or for holding the cutter to any set horizontal position relative to the slide bar 1.

Spring 5, as shown in Figures 1, 3, 4, and 5, respectively, around cutter post and engaging 50 washer 6 and under face of cutter 3, is under compression and when the adjusting and the retaining nut 4, shown in Fig. 1 and other views, is backed-off the spring forces the cutter shaft and cutter higher above bar 1; the spring thus holds 55

the cutter to changed elevated position with respect to abutment points of contact and slide bar.

It will be seen that the relative clearance from edge of the cutter to its heel, not contacting the piston, may be increased or decreased by raising or lowering the same in position horizontally relative to the handle portion of bar 1, Fig. 1. This allows nicety of adjustment for obtaining 10 smoothness of operation and non-digging of tool.

When used without spring 5 as shown in Fig. 6, the device is grasped in the hand to revolve same around the piston and finger and thumb are applied to nut 4 and post 2 in order to hold the 15 cutter to height adjusted cutting position.

When the device is used with longitudinal compression spring 7, intermediate to post 2, and retaining nut 8 fixed by pin 9 as on end of handle as shown in Fig. 1, feed of the cutter into the 20 cut is effected by spring pressure, whereas without this spring and as shown in Fig. 5 it is necessary to produce longitudinal hand pressure against the cutter shaft assembly to effect the cut while revolving the device around the piston in 25 the groove.

The foregoing explanation and description is intended to convey the principal objects of my invention. Considerable deviation from the exactness of detail may be made and still remain 30 within the scope of claims as herein made and as follows:

I claim as my invention:

1. A piston ring groove scraper and deepener comprising: a straight bar having one end bent 35 back upon itself to form two spaced piston engaging points; a cutter post mounted on the straight portion of said bar slidable longitudinally of said bar along the straight portion of said bar and adjustably movable transversely of the bar, said post having a slot therein to receive said bar; a 40 cutter on one end of said post arranged to engage the piston ring groove oppositely of said bent end of the bar; a compression spring on said post between said bar and said cutter; and means 45 on the other end of said post yieldingly held against said bar by said spring for retaining said post on said bar.

2. A piston ring groove scraper and deepener comprising: a straight bar having one end bent back upon itself to form two spaced piston 50 engaging points; a cutter post mounted on the straight portion of said bar slidable longitudinally of said bar along the straight portion of said bar and adjustably movable transversely of the bar, said post having a slot therein to receive said bar; and a cutter on one end of said post arranged to engage the piston ring groove oppositely of 55 said bent end of the bar.

on said bar along the straight portion of said bar and movable transversely of the bar, said post having a slot therein to receive said bar; a cutter on one end of said post arranged to engage the piston ring groove oppositely of said bent end of the bar; a compression spring on said post between said bar and said cutter; and a nut threaded on the other end of said post yieldingly held against said bar by said spring for retaining 10 said post on said bar.

3. A piston ring groove scraper and deepener comprising: a straight bar having one end bent back upon itself to form two spaced piston engaging points; a cutter post mounted on the straight portion of said bar slidable longitudinally of said 15 bar along the straight portion of said bar and movable transversely of the bar, said post having a slot therein to receive said bar; a cutter on said post arranged to engage the piston ring groove oppositely of said bent end of the bar; a compression spring on said post between said bar and said cutter; means on said post yieldingly held against said bar by said spring for retaining said post on said bar; a head on said bar; and a compression spring on said bar between said post and 25 said head.

4. A piston ring groove scraper and deepener comprising: a straight bar having one end bent back upon itself to form two spaced piston engaging points; a cutter post mounted on the 30 straight portion of said bar slidable longitudinally of said bar along the straight portion of said bar and adjustably movable transversely of the bar, said post having a slot therein to receive said bar, a cutter on one end of said post arranged to engage the piston ring groove oppositely of said 35 bent end of the bar; an abutment member on the end of the straight portion of said bar; and a compression spring on said bar between said post and said abutment member. 40

5. A piston ring groove scraper and deepener comprising: a straight bar having one end bent back upon itself to form two spaced piston engaging points; a cutter post mounted on the straight portion of said bar slidable longitudinally of said 45 bar along the straight portion of said bar and adjustably movable transversely of the bar, said post having a slot therein to receive said bar; and a cutter on one end of said post arranged to engage the piston ring groove oppositely of 50 said bent end of the bar.

CHARLES D. STROMGREN.
